UNITED STATES PATENT OFFICE

152,153

DESIGN FOR A STEP

Norman J. Harvey, Bellevue, Nebr.

Application May 1, 1946, Serial No. 129,169

Term of patent 14 years

(Cl. D15—8)

To all whom it may concern:

Be it known that I, Norman J. Harvey, a citizen of the United States, residing at Bellevue, in the county of Sarpy and State of Nebraska, have invented a new, original, and ornamental Design for a Step, of which the following is a specification, reference being had to the accompanying drawing, forming part thereof, in which

Figure 1 is a view in perspective of a step, embodying my new design.

Figure 2 is a view in top elevation of the step, illustrated in Figure 1.

Figure 3 is a view in front elevation of the step, and

Figure 4 is a view in side elevation of the same device.

I claim:

The ornamental design for a step, as shown.

NORMAN J. HARVEY,
